UNITED STATES PATENT OFFICE.

HERBERT W. FIES, OF CLEVELAND HEIGHTS, OHIO, ASSIGNOR OF ONE-HALF TO MAX L. JEFFREY, OF CLEVELAND, OHIO.

SAFETY-SHOE FOR LADDERS.

1,379,808.

Specification of Letters Patent. Patented May 31, 1921.

Application filed July 2, 1920. Serial No. 393,510.

To all whom it may concern:

Be it known that I, HERBERT W. FIES, a citizen of the United States, and a resident of Cleveland Heights, county of Cuyahoga, 5 and State of Ohio, have invented a new and useful Improvement in Safety-Shoes for Ladders, of which the following is a specification, the principle of the invention being herein explained and the best mode in which 10 I have contemplated applying that principle, so as to distinguish it from other inventions.

The present invention, relating, as indicated, to safety shoes for ladders and the 15 like, is directed to an improved support or shoe to receive the lower end of a ladder or similar device for maintaining the same against movement over the floor when in use. One of the chief objects of the invention is 20 the provision of a device of a simple, inexpensive character which may safely be used to fasten the lower end of a ladder against accidental movement along a floor. To the accomplishment of the foregoing and related ends, said invention, then, consists of the means hereinafter fully described and particularly pointed out in the claim.

The annexed drawing and the following 30 description set forth in detail certain mechanism embodying the invention, such disclosed means constituting, however, but one of various mechanical forms in which the principle of the invention may be used.

In said annexed drawing:

35 Figure 1 is a view in perspective, showing the ladder in an inclined position and mounted upon my improved shoe; Fig. 2 is a side elevation of a shoe showing the ladder supported thereon; Fig. 3 is a bottom plan 40 view of the shoe; and Fig. 4 is an end elevation of the same.

In Fig. 1 there is shown a ladder of common construction, consisting of parallel members 1 and rungs 2. In using such ladders in factories where the floors are of concrete or similar material many accidents 45 have occurred due to the fact that the ends 3 of the ladder are likely to slip along the floor and allow the ladder to fall, there being 50 no secure engagement between the ends of the ladder and the floor.

My improved shoe consists of a member 4 which is provided with a horizontal portion

or plate 5 having upturned parallel sides 6 and downturned lugs or projections 7, which 55 are preferably stamped out from the body of the plate 5. Each of the upstanding portions 6 is provided with an opening 8 there-through, adapted to receive a bolt 9, and these portions 6 are so spaced as to receive 60 therebetween one of the ends 3 of the ladder, which must also be provided with a suitable opening to receive the bolt 9.

The engagement between the bolt 9 and ladder ends 3, should obviously be sufficiently free to allow of pivotal movement of the ladder to accommodate it to various inclined positions.

In use, each end 3 of the ladder is mounted in one of the shoes 4 and is secured thereto by means of the bolts 9. When placed in position the triangular sharpened engaging lugs 7 on the lower side of the plate engage against the floor and grip the same sufficiently to prevent accidental movement of 75 the ladder under ordinary conditions of use.

The present device can be formed entirely from sheet metal, the upturned end portions or flanges being pressed up from a flat sheet, while the engaging lugs can be 80 stamped out in the same manner. The cost of manufacturing the shoe is therefore relatively very little, and a very strong shoe can be made in this way at an extremely low cost. A further advantage of the device is 85 that it is relatively light, as distinguished from other shoes which are sometimes used and which are formed of heavy castings, and it therefore adds but little to the weight of 90 the ladder and allows the same to be readily moved from place to place.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

A shoe for ladders and the like, comprising a sheet metal member of uniform thickness provided with a series of integral gripping elements formed at each of its end portions and bent downwardly therefrom, a series of gripping elements located centrally

in each half of said shoe and directed similarly to said end gripping members, intermediate series of gripping elements located between said first mentioned elements and 5 stamped downwardly from said plate in an opposite direction and upwardly extending flanges on opposite sides of said member

formed from the edge portions of the metal member, said flanges being adapted to removably receive the base of the ladder there- 10 between.

Signed by me, this 28 day of June, 1920.

HERBERT W. FIES.
